US00D714813S

(12) **United States Design Patent**
Oda et al.

(10) **Patent No.:** **US D714,813 S**
(45) **Date of Patent:** **** Oct. 7, 2014**

(54) **ELECTRONIC CAMERA**

(71) Applicant: **FUJIFILM Corporation**, Tokyo (JP)

(72) Inventors: **Akemi Oda**, Tokyo (JP); **Chinatsu Watanabe**, Tokyo (JP); **Yuuki Okabe**, Tokyo (JP); **Atsushi Misawa**, Saitama (JP)

(73) Assignee: **Fujifilm Corporation**, Tokyo (JP)

(**) Term: **14 Years**

(21) Appl. No.: **29/477,528**

(22) Filed: **Dec. 23, 2013**

Related U.S. Application Data

(62) Division of application No. 29/448,035, filed on Mar. 8, 2013, now Pat. No. Des. 700,193, which is a division of application No. 29/415,561, filed on Mar. 12, 2012, now Pat. No. Des. 681,652, which is a division of application No. 29/384,841, filed on Feb. 4, 2011, now Pat. No. Des. 659,152, which is a division of application No. 29/363,591, filed on Jun. 11, 2010, now Pat. No. Des. 633,509, which is a division of application No. 29/350,551, filed on Nov. 18, 2009, now Pat. No. Des. 622,729, which is a division of application No. 29/274,033, filed on Mar. 22, 2007, now Pat. No. Des. 609,714.

(57) **CLAIM**

We claim the ornamental design for an electronic camera, as shown and described.

DESCRIPTION

FIG. 1 is a front view of an electronic camera according to a first embodiment of the present design;

FIG. 2 is a rear view thereof;

FIG. 3 is a top view thereof;

FIG. 4 is a bottom view thereof;

FIG. 5 is a right side view thereof; and

FIG. 6 is a left side view thereof.

FIG. 7 is a front view of the electronic camera according to a second embodiment of the present design;

FIG. 8 is a rear view thereof;

FIG. 9 is a top view thereof;

FIG. 10 is a bottom view thereof;

FIG. 11 is a right side view thereof; and,

FIG. 12 is a left side view thereof.

Broken lines and unshaded portions contained within broken line are not claimed.

1 Claim, 6 Drawing Sheets
